(Cl. D26—14)

To all whom it may concern:

Be it known that I, Gustav F. Braun, a citizen of the United States, residing at Elizabeth, in the county of Union and State of New Jersey, have invented a new, original, and ornamental Design for Hand Microphone, of which the following is a specification, reference being had to the accompanying drawing, forming part thereof.

Figure 1 is a front view of a hand microphone embodying my novel design.

Figure 2 is a side view of the hand microphone shown in Figure 1..

Figure 3 is a rear view of the hand microphone shown in Figure 1.

Figure 4 is an end view of the microphone shown in Figure 1.

I claim:

The ornamental design for a hand microphone, as shown.

GUSTAV F. BRAUN.
